UNITED STATES PATENT OFFICE

2,660,418

LOW HEIGHT SHORTWALL MINING
MACHINEArthur L. Lee, Upper Arlington, Ohio, assignor, by
mesne assignments, to The Jeffrey Manufacturing Company, a corporation of Ohio

Application April 6, 1945, Serial No. 586,979

3 Claims. (Cl. 262—30)

1

This invention relates to a mining machine of the shortwall type.

An object of the invention therefore is to provide a mining machine which has a very low overall height and thus can be used to cut kerfs in very low seam coal, while at the same time providing a mining machine of this type which is very flexible in its operation.

Another object of the invention is to provide an improved motor construction for a low height mining machine in which the parts are so arranged that a path is provided for a cutter chain which is generally below the major portion of the motor, but lies in a generally horizontal plane which passes through the motor rotor or above a portion of the exposed face of a bottom pole shoe and in a more specific form which also involves a pair of field poles which are inclined upwardly and outwardly and thus make an acute angle with a horizontal plane which preferably passes through the axis of the rotor and substantially through the centers of the faces of the pole shoes for said inclined poles.

Other objects of the invention will appear hereinafter, the novel features and combinations being set forth in the appended claims.

In the accompanying drawings,

Fig. 1 is a plan view of a shortwall type machine which incorporates the features of my invention, the cutter bar being shown cut short;

Fig. 2 is a side elevational view of the machine of Fig. 1;

Fig. 3 is a vertical sectional view of the rear portion of the machine, taken substantially through the center thereof, showing particularly the machinery frame compartment with the gummer removed, some parts being eliminated in the interest of clearness; and

Fig. 4 is a combination front elevational view of the mining machine showing an extension of the cutter bar support and cutter chain in section and a transverse section through the motor of said mining machine.

Referring particularly to the drawings and to the shortwall machine which is therein disclosed and in which there is incorporated the various features of my invention, it may be pointed out first that one of the important considerations which dictates some of the structure is the overall height of the mining machine. This mining machine is of the type which is adapted to rest on and slide over the mine floor as a unit while cutting a kerf or, in other words, is of the well known shortwall type. As a consequence, it is desirable to make its overall height a minimum,

2

to the end that it may be used in very low seam mines.

Referring first to Figs. 1 and 2 of the drawings, the machine includes a main frame 40 which in practice is preferably formed of two substantially independent frames including a forward motor frame or section 41 and a rearward machinery frame or section 42, the two frames or sections 41 and 42 being removably connected together as by machine screws or bolts. Removably attached to the rear end of the machinery frame or section 42 is a gummer or cuttings removing mechanism 43 which is optionally employed or omitted.

Extending forwardly from the motor frame or section 41 is a kerf-cutting mechanism 44 including an elongated cutter bar 45 which is of substantially standard construction, except for certain differences hereinafter pointed out, upon which there is mounted an endless cutter chain 46 provided with removable and reversible cutter bits 47. As is well known, the shortwall type of mining machine is adapted to be fed as a unit over the mine floor while cutting a kerf, the kerf being cut by first sumping the cutter bar into the solid coal and then feeding the machine laterally or across the coal face, all the while the kerf cutting mechanism 44 is in operation.

To effect the feeding of the mining machine as a unit, both at a kerf cutting speed and at a handling or higher speed and in reverse directions, the machine includes a pair of feed cable or rope drums 48 and 49 mounted on horizontal axes which are preferably in alignment, one on one side of the machine, the other on the other, as clearly illustrated in Fig. 1 of the drawings.

It may also be noted that the overall height or vertical dimension of the mining machine is substantially equal to the diameter of drum 48 or 49 and the top of the drum 48 or 49 is substantially at the top of said frame 40.

Drums 48 and 49 are provided with feed ropes or cables 50 and 51, respectively, which are adapted to be reeved about the sheaves of similar right and left hand rear sheave assemblies 52 and 53, respectively, and/or similar right and left hand front sheave assemblies 54 and 55, respectively.

In Fig. 1 of the drawings the machine is illustrated with the ropes 50 and 51 reeved about the pulleys 52 and 55 to effect a lateral feeding of the machine to the left, as viewed from the rear thereof, or upward, as viewed from the drawings.

By the mere expedient of reeving rope 50 about the sheave of front assembly 54 and reeving rope 51 about the sheave of sheave assembly 53 and 55 making the necessary operating adjustments on

the machine, it may be fed to the right, reversely of that illustrated in said Fig. 1 of the drawings.

By extending both of the feed ropes 50 and 51 directly forwardly and to mine jacks, the machine may be fed forwardly and dumped into the solid coal. By extending the rope 50 rearwardly and around an auxiliary sheave 56, then laterally to a central sheave not illustrated but which is common on machines of this type, the machine can be pulled rearwardly away from the mine face and may be loaded onto a truck in a manner well understood in the operation of shortwall machines.

The shortwall mining machine illustrated is, of course, adapted to rest on and slide over the mine floor when in operation and the supporting surfaces of the machine are provided largely by four spaced hydraulic piston jacks or motors (when employed), those at the rear being designated 57 and those at the front being designated 58. These hydraulic jacks provide for adjusting the elevation of the cutter mechanism 44 or, in other words, the effective height of the machine and also provide for adjusting the inclination or tilt thereof on right angularly related axes relative to a horizontal plane.

Attention is now directed particularly to Fig. 3 of the drawings and to some of the machinery or gearing which is contained within the machinery section 42 which includes the drive gearing leading to the cutter chain 46 and to the drums 48 and 49, as well as other mechanism.

Extending from the motor section 41 into the machinery section 42 is the end of a hollow drive shaft 59 which is supported at its outer end on an anti-friction bearing 60 which in turn is supported on a web or integral bracket formed on the frame 42 which provides a substantially totally enclosing housing for the machinery or gears therein.

Keyed adjacent the end of the shaft 59 is a pinion 61 which meshes with a larger pinion 62 keyed to a shaft 63 having an integral bevel pinion 64, the shaft 63 being mounted in spaced bearings within the housing or frame 42. Pinion 64 meshes with a large bevel ring gear 65, the hub of which is mounted in a roller bearing 66 carried in a bearing cup in a removable top plate 67 which is removably attached to the frame 42 and forms a part of the enclosure or housing provided thereby. The hub of ring gear 65 is also mounted on spaced needle bearings 68 by which it is mounted for free rotation on a vertical or upstanding shaft 69, to the bottom of which a drive sprocket 70 for the cutter chain 46 is provided.

The drive shaft 69 extends through a hole in an elevated integral bottom plate 71 of the frame or section 42, which is preferably formed as a single steel casting, and is supported principally on a roller bearing 72 received in a removable cup 73 which is attached to the bottom plate 71 as by machine screws.

Since the sprocket 70 is, of course, exposed to the atmosphere and is outside the enclosure provided by the enclosing frame or section 42, within which enclosure there is a considerable amount of lubricating oil, though it is not filled with oil, oil seals are provided to prevent oil leakage. First of all, there is a pair of oil seals 74 provided adjacent the opening through which shaft 69 extends and a ring 75 which preferably has a tight fit with the shaft 69. Lubrication for the bearing 72 is provided by an oil catcher 76 and a pipe 77 which leads by way of a passageway around

the seals 74 to the bearing 72. Oil seals at the bottom of the bearing 72 between the bottom of the cup 73 and the sprocket 70 are provided by a piston ring 78, a felt packing 79 and a labyrinth type packing 80. Obviously, other forms of oil or grease packing may be employed for those illustrated and described.

From the above description it is evident that the shaft 69 is supported in the frame or section 10 42 by the bearing 72 at the bottom and by the combined actions of the top bearing 66 and the needle bearings 68 through the intermediary of the hub of ring gear 65. It is further evident 15 from the above description that there is not a permanent or direct driving connection from the ring gear 65 to the shaft 69, but on the contrary the ring gear 65 is free to rotate on said shaft 69. To support the ring gear 65 on the shaft 69 against downward axial movement, there is a 20 thrust ball bearing 81 interposed between a shoulder on the shaft 69 and the bottom of the hub of said gear 65.

Mounted concentric with the ring gear 65 and the shaft 69 and keyed onto the hub of said ring 25 gear 65 is a bevel gear 82. Gears 65 and 82 therefore always rotate together and each is directly driven from the drive shaft 59 and always rotates with it.

At its bottom portion the gear 82 forms a driving portion of a jaw clutch and is provided with 30 clutch dogs 83. Providing the driven portion of said clutch is a shiftable collar 84 having dogs adapted to be engaged with or disengaged from the dogs 83. Collar 84 is shiftable upwardly 35 and downwardly on the shaft 69 and is splined or keyed thereto so that whenever it is driven, a driving relation is effected to said shaft 69. A bifurcated shipper 85 mounted on a rotary horizontal clutch shaft 86 is provided for operating the clutch 83—84, which clutch, obviously, is the clutch for effecting a driving or non-driving relation from the driving motor 154 to the cutter chain 46.

The operating shaft 86 is connected to be operated by an operating lever and handle 91 on each side of the mining machine so that the clutch for engaging and disengaging the cutter chain 46 may be operated from either side of the machine.

Attention is now directed particularly to Fig. 4 of the drawings and to an important relation of parts which makes for a machine particularly of the shortwall type having a minimum overall height and particularly, but not necessarily so, when a direct current type motor is employed. It is, of course, to be understood that the structure illustrated on opposite sides of the vertical plane dividing the machine in Fig. 4 is duplicated on the other side.

The direct current motor 154 disclosed is of the consequent pole type, there being four pole shoes, three of which are visible in said Fig. 4 of the drawings, which are the top and bottom consequent pole shoes 196 and 197, respectively, and the left hand main pole shoe 198. The four pole shoes 196, 197, 198 and its right hand duplicate are substantially equally spaced about the periphery of the rotor or armature 155 and, as illustrated, a vertical plane through the axis of the rotor 155 bisects the pole shoes 196 and 197 and a horizontal plane therethrough bisects the shoe 198 and its complement.

The shoes 196 and 197 are removably bolted to top and bottom portions of the iron of the frame 41 which forms a magnetic field path for

the flux developed by two compound field coils or windings, one of which is seen at 199 and which is wound on a main pole 200. The complementary shoes and main poles, one of which is seen at 198 and 200, are removably attached to the frame 41 by elongated bolts 201 provided with appropriate clamping nuts.

Between each of the main shoes 198 and the top shoe 196 is a removable interpole 202, removably attached to the frame 41 as by screws 203 and provided with a compensating winding or coil 204 to aid in the commutation in a manner well understood in this art.

It is to be particularly noted that the longitudinal axis of the two main poles, one of which is seen at 200, slopes upwardly and outwardly with respect to a horizontal plane through the axis of the rotor 155 or a horizontal plane which bisects the arcuate faces of the pole shoes, one of which is seen at 198, adjacent the rotor 155. This angle of inclination between said axis and said horizontal plane is approximately 15°. Thus, without disturbing the proper spacing of the shoes 196, 197 and 198 which should be substantially equally spaced about the periphery of the rotor 155, a passageway 206 is provided adjacent the bottom and along each side of the motor 154, the lateral boundaries of which passageways are determined by guide ribs 141. Stated another way, the motor frame portion of the frame section 41 is provided with axial or longitudinally extending lateral or side recesses, adjacent each side and bottom, which are seen at 206. The motor frame portion of said frame section 41 is that portion thereof which provides the magnetic path for the flux developed by the field windings 199. The lateral limits or sides thereof may be considered as defined by the outside surfaces of the iron of frame 41 to which the poles 200 are attached.

These passageways 206 provide adequate room for the cutter chain 46 and its bits 47 to travel about the cutter bar 45 as well as along the bottom side portions of the motor 154, as the tight and slack runs travel toward and from the drive sprocket 70, while at the same time making possible a machine of very low overall height since practically no additional height is required to accommodate the cutter chain, and consequently the height of the machine is determined almost entirely by the minimum height of the motor 154.

Concerning the particular relation which exists between the cutter chain 46 and the motor 154, as well as the guide means for the chain 46 along said motor, it is to be noted that the guide means for said chain 46 adjacent the frame of said motor 154 is provided by an elongated chain receiving groove 207 on each side of the motor and adjacent the passageway 206. Each groove 207 has its inner and upper side walls, as viewed in Fig. 4, formed by the iron of the motor frame 41 and is provided with a removable L-shaped wear and retaining strip 208 which is rigidly attached to said frame 41. The bottom side wall of each groove 207 is provided by the upper surface of an arm of the cutter bar extension 189 and it is provided with a removable L-shaped wear and retaining strip 209 attached thereto.

The structure of the cutter bar extension 189 and its attaching tab 194 and screw 195 are claimed in my divisional application, Serial No. 290,160, filed May 27, 1952, now Patent No. 2,637,543, dated May 5, 1953.

Thus the frame 41 and the two branches of

the cutter bar extension 189 co-operate to provide guiding and retaining means for the cutter chain 46 in its travel along the sides of the bottom portion of the motor 154 as it approaches 5 and leaves the sprocket 70. The grooves 207, of course, continue into similar grooves in the main body of the cutter bar 45, the structure of which is well known in the mining machine art.

The resulting structure which is produced by 10 the above described relation of parts includes the following features. First of all, it is to be noted by reference to Fig. 4 of the drawings that a horizontal plane through the top or even through

the center of the cutter chain 46 intersects the bottom of the rotor 155 and in fact is entirely 15 above the bottom shoe 197 and is appreciably 20 above the bottom or lowest portion of the arcuate face of said shoe 197 which is adjacent the rotor 155. Furthermore, a plane through the 25 bottom side wall of the groove 207 or through the bottom of the cutter chain 46, passes through the shoe 197 and is closely adjacent to the bottom of the rotor or armature 155 and is above the bottommost point of contact between the shoe 25 197 and the iron of frame 41.

Stated another way, the entire cutter chain 46, as it travels along the sides of the motor 154, is entirely above the iron forming the field structure of said motor at its bottom and is entirely 30 above the area of contact between the bottom removable shoe 197 and the magnetic frame of said motor 154. It is furthermore to be noted that the cutter chain 46 in traveling through the passageways or recesses 206 is located below the 35 frame of the electric motor. For example, the reversely traveling runs of said chain 46 traveling through said recesses or passageways 206 are located inwardly of upright planes which define the lateral or side limits of the motor frame.

40 This is an important feature of my invention. In some of its broader aspects, as defined in the claims, some of the benefits of my improved construction are realized so long as at least a part 45 of the cutter chain 46 is inwardly of said upright or vertical plane defining the lateral edges of the frame of the motor proper, particularly when this condition occurs concurrently with one in which at least a portion of said cutter chain 46 and its groove or guide 207 also passes through a horizontal plane which intersects the rotor 155 or is within the limits defined by the topmost portion of the shoe 197, when it is present in the machine, and the bottommost portion of the surface which has contact with the bottom of said shoe 197, which surface, of course, constitutes the surface of the frame of the electric motor to which the shoe or pole 197 is removably attached. This surface as 50 illustrated is arcuate in construction as is the face of the shoe 197, and the low point of said 55 contacting surface of the bottom plate of the motor frame is directly below the axis of the motor shaft 59, or, stated another way, is in a vertical or upright plane which passes through the axis of the shaft 59 of said electric motor.

60 As previously mentioned, the motor 154 may be of the alternating current type and the frame illustrated is designed with this thought in mind. To this end, the rotor 155 will, of course, be wound as an alternating current rotor preferably of the induction type. The field structure will be of the alternating current type and include a plurality of stacked circular grooved laminations stacked on the axis of the rotor 155 and in the iron of the motor frame 41. To accommodate 70 this, the shoes 196, 197 and 198 are removed, as

are the coils 199 and 204, together with the interpoles 202. When this is done the slotted stator field discs may be inserted and have close contact with certain portions of the iron of the field or frame, particularly those where the shoes 196 5 and 197 are now shown, as well as having contact with the poles 200.

Obviously those skilled in the art may make various changes in the details and arrangement of parts without departing from the spirit and scope of the invention as defined by the claims hereto appended, and I therefore wish not to be restricted to the precise construction herein disclosed.

A number of the features herein disclosed are 15 disclosed and claimed in my co-pending applications Serial Nos. 642,862, now Patent No. 2,162,363; 674,293, now abandoned; 676,200, now Patent No. 2,638,332; 679,302, now Patent No. 2,441,495; and 679,303, now Patent No. 2,530,249. 20

Having thus described and shown an embodiment of my invention, what I desire to secure by Letters Patent of the United States is:

1. A mining machine motor structure including a magnetic field frame, an armature mounted in said frame for rotation on a normally substantially horizontal axis, a pair of main field poles on opposite sides of said motor having pole shoes adjacent said armature and having outwardly and upwardly inclined axes relative to the 25 axis of said armature, top and bottom main pole shoes connected to said frame and located adjacent said armature and being located between said first named pole shoes, and cutter chain guide means on opposite sides of the bottom pole shoe the tops of which guides are in a plane above the bottom of the face of said bottom pole shoe, said guide means also being inwardly of normally vertical planes along the outer sides of said magnetic field frame.

2. A direct current mining machine four pole motor including two generally opposite main field poles having windings thereon, the axes of said poles being inclined from the motor axis up-

wardly and outwardly relative to a generally horizontal plane through said motor axis and making an angle of approximately 15 degrees with said horizontal plane and also including top and bottom main poles between said first two named poles and in a vertical plane through the axis of said motor.

3. A direct current mining machine four pole motor including two generally opposite main field poles having windings thereon, the axes of said poles being inclined from the motor axis upwardly and outwardly relative to a generally horizontal plane through said motor axis, and also including top and bottom main poles between said first two named poles and in a vertical plane through the axis of said motor.

ARTHUR L. LEE.
